UNITED STATES PATENT OFFICE.

HERBERT W. OWEN, OF LEWISTON, MAINE, ASSIGNOR TO DRAPER CORPORATION, OF HOPEDALE, MASSACHUSETTS, A CORPORATION OF MAINE.

PROCESS OR METHOD OF AND MEANS FOR FINISHING THE EDGES OF WOVEN FABRICS.

1,307,694.

Specification of Letters Patent. Patented June 24, 1919.

Application filed December 6, 1918. Serial No. 265,601.

To all whom it may concern:

Be it known that I, HERBERT W. OWEN, a citizen of the United States, and a resident of Lewiston, county of Androscoggin, and 5 State of Maine, have invented an Improvement in Processes or Methods of and Means for Finishing the Edges of Woven Fabrics, of which the following description, in connection with the accompanying drawings, 10 is a specification, like characters on the drawings representing like parts.

The invention to be hereinafter described relates to the process of and means for finishing the edges of woven fabrics.

15 Woven fabrics frequently have unwoven portions of weft or filling threads extending along or from the longitudinal edges or selvages thereof which remain as an incident to the weaving operation. In weaving 20 gingham with two or more shuttles each containing a different kind or character of weft or filling, for instance, it is the usual practice to employ one shuttle for a series of picks and then another, the weft or filling from the temporarily idle shuttle being 25 permitted to float or extend along the edge or selvage of the fabric until such idle shuttle is again called into play. Thus a series of floating loops of unwoven portions of 30 weft or filling are formed along the cloth edge or selvage which must be subsequently removed. Heretofore this has been done either by singeing the cloth edge or by cutting the loops close to the cloth by hand. In 35 either case, however, the cloth edge or selvage is liable to be injured. In other fabrics where during the weaving operation the weft or filling is parted by a feeler thread cutter or a temple thread cutter, or both, an 40 objectionable trailing end of the weft or filling also projects from the cloth edge or selvage.

45 Regardless of how such unwoven floating or trailing ends are formed, it is important that they be removed in order that the cloth edge or selvage may present a clear and finished condition. An important feature of the present invention, therefore, consists of a process or method for finishing the 50 fabric by cutting or removing the unwoven portions of weft or filling from the edge or selvage of the fabric and close thereto without liability of injury to the fabric itself. In carrying this feature of the invention 55 into practical effect the edge of the cloth is

subjected to the action of induced air currents to distend or extend the unwoven portions of thread and while the unwoven portions of thread are so distended they are carried into the field of a guarded thread 60 cutter which parts the unwoven portions of thread close to the cloth edge or selvage, and is prevented from injuring the cloth.

To accomplish the objects of the invention the new process or method may be practised 65 by variously contrived means but it has been found best to treat the fabric after its has been rolled or folded into a package or bolt form with the unwoven threads at the end, so that the body of the fabric itself may co- 70 act with the guarding surface to protect the edge or selvage while the unwoven threads may be extended through the surface by induced air currents and there cut.

75 Another important feature of the invention consists in a thread cutter operating in a plane non-coincident with a surface over which the edge of the cloth may be moved and means for inducing air currents across the edge of the cloth to carry the unwoven 80 portions of threads into the field of operation of the thread cutter. In connection with this aspect of the invention it is desirable to provide for adjustment of the thread cutter toward and from the protecting surface so that the unwoven portions of threads in different fabrics may be cut appropriately 85 close to or farther from the selvage edge of the cloth.

90 The above and other features of the invention involve novel combinations of parts as will be hereinafter more fully described and pointed out by the claims.

In the drawings:

95 Figure 1 is a perspective view of a machine embodying the mechanical features of the invention and adapted to practise the process or method;

Fig. 2 is an enlarged sectional detail on the line 2-2 of Fig. 1 showing the relative 100 position of parts having to do more particularly with the supporting surface, the thread cutter and air conduit;

Fig. 3 is an enlarged detail showing a convenient form of block for supporting the 105 thread cutting mechanism and for connection with the air conduit.

In finishing the longitudinal edge or selvage of a woven fabric it is essential that any unwoven portions of thread may be 110

trimmed with accuracy close to the longitudinal edge or selvage and that the edge or selvage itself may be effectively protected from injury by the trimming means. The machine illustrated in the accompanying drawings has been found to be practically efficient in securing the end results sought and carrying out the new process or method. In the drawing a suitable base 1 for sustaining portions of the machine may be mounted upon a column or legs for maintaining it in suitable position convenient for the attendant. Rising from the base 1 are the side members 2 and end member 3 of an inclosing casing on which is secured a guiding or supporting surface 4. The guiding or supporting surface 4 is formed to provide a suitable support for a package or bolt of cloth 5 which may be moved over such surface as indicated in Fig. 1 by the machine attendant.

Within the inclosing casing hereinbefore described and below or non-coincident with the plane of the guiding or supporting surface 4 is a thread cutting device which may be variously contrived, and adjacent thereto the guiding or supporting surface for the cloth package or bolt is provided with an opening through which air currents are induced in order to carry unwoven portions of weft or filling threads into the field of action of the cutting device as the cloth package or bolt is moved across the opening and above the cutting device as indicated in Fig. 1. In the present instance of the invention and within the casing heretofore described is a support 6, Fig. 3, on which is mounted a block 7 having a cavity or depression 8 with which is connected one end 40 of an air conduit 9. The block 7 may be variously contrived but in the present instance is formed of cast metal as a convenient manner of fabricating the block, and the top surface of the block 7 is preferably 45 extended over a substantial portion of the guiding or supporting surface 4 and substantially coincident with the plane of such surface, as indicated in Figs. 1 and 3. The block 7 is secured to the support 6 by appropriate means such, for instance, as the screws 10.

The thread cutting device as hereinbefore stated may be variously formed and in the present instance of the invention it comprises a sleeve 11 having secured thereto or formed integral therewith the head portion 12 to which is secured the fixed cutting member 13 as indicated in Figs. 1 and 2. This fixed cutting member may be secured to the head by appropriate means, such, for instance, as the screws or bolts 14, as indicated by dotted lines in Fig. 1, and its cutting end portion is provided with the separated fingers or forks 15 between which the 60 unwoven portions or weft or filling threads

may be projected. The head 12 is provided with a guide or lug portion 16, Fig. 2, between which and the fixed cutting member 13 is the movable cutting member 17, Fig. 2, said movable cutting member being provided with the cutting portions 18 and being guided upon the lug or projection 16 of the head. The movable cutting member 17 has a slotted portion 19 extended therefrom which embraces a crank pin 20 secured to the disk 21 on the driving shaft 22 which latter extends through the sleeve 11. From the construction described it will be apparent that upon rotation of the shaft 22 the movable cutting member 17 will be reciprocated longitudinally to the fixed member 13 and any threads which may be projected between the end finger portions of the fixed and movable cutting members will be appropriately cut. In order to maintain the fixed and movable cutting members in proper co-operating relation, a bolt 23 is extended from the fixed cutting member through the lug or projection 16 of the head and passes through an elongated opening 24 of the movable cutting member. Between the lug 16 and the nut 25, the pin 23 is provided with a spring 26 normally acting to hold the fixed cutting member in its proper working relation with the movable cutting member, the construction being such that any wear of parts due to the relative reciprocation of the two cutting members will be automatically compensated by the spring 26.

The field of operation of the thread cutter, as will appear from the above description, is non-coincident with or slightly below the plane of the guiding or supporting surface on which the bolt of cloth 5 is adapted to be moved, and in order that the proximity of such cutting field may be adjusted as circumstances may dictate, suitable means is provided for adjusting the cutting device toward and from the plane of the cloth package supporting surface. In the present instance of the invention such adjusting means comprises a screw 27, Fig. 2, threaded through the block 7 and provided with a lock nut 28, the end of the screw being adapted to support the head 21 of the cutting device. By proper manipulation of the adjusting device the head 21 and, perforce, the thread cutter may be adjusted toward and from the plane of the supporting surface 4.

It is desirable that the unwoven portions of weft or filling threads represented at 29 be extended or projected into position for the action of the thread cutter as the cloth package or bolt 5 is moved over the supporting surface or, as in the present instance of the invention, the block 7, has an opening between the cutting device and the end of the cavity 8 and with such opening the air con-

duit 9 communicates. Connected with the air conduit 9, as indicated in Fig. 1, is a tubular conduit 30 which communicates with an air suction fan 31, the construction 5 being such that the unwoven portions of weft or filling threads along the selvage of the cloth package will be subjected to induced currents of air as the end of the package is moved over the opening in the surface 10 4 or block 7, and such unwoven portions of weft or filling threads will be distended or extended into such cavity so that as the cloth package or bolt 5 is moved in the direction of the arrow, indicated in Fig. 2, such 15 distended or extended weft or filling threads will be brought into the field of action of the thread cutter and severed from the cloth selvage. The severed ends of weft or filling threads will be carried by the air currents 20 into the conduit 9 and may be collected at a convenient point in the air system. If desired the air conduit may have a valve 32, Fig. 1, whereby the air induced currents may be interrupted.

25 The shaft 22 may be driven from any suitable source of power to cause the thread cutter to be actuated and in the present instance of the invention is operated from an electric motor indicated at 33, Fig. 1. In this 30 instance of the invention the motor 33 is mounted upon the head plate or support 1 and is connected by the motor shaft 34 and sleeve 35 and short shaft 36 with the driving shaft 32; the construction being such 35 that upon actuation by the motor the shaft 22 may be appropriately rotated to operate the thread cutting device. By the connection described between the shaft 22 and the motor, the parts may be readily assembled 40 or taken apart.

From the construction described as a practical embodiment of the invention, it will be noted that a cloth package or bolt having unwoven portions of weft or filling threads 45 at one end may be supported upon and guided by the supporting surface 4 and then moved by the attendant over the opening through such surface in advance of the thread cutter. As the cloth package or bolt 50 is thus moved, the induced air currents act upon the unwoven portions of filling threads and extend or distend them so as to carry them into the field of action of the thread cutter as the cloth package or bolt is moved 55 over the guiding or supporting surface. By reason of the fact that the cloth is formed into a package or bolt the induced air currents are enabled to act upon the loose weft or filling ends and carry such ends into the 60 field of action of the thread cutter without exposing the edge of the cloth itself to injury.

Claims:

1. The process or method of removing 65 threads from a cloth selvage after the cloth

has been formed into a package, which consists in subjecting the end of the cloth package to the action of air currents to extend the threads from the end of the cloth package, and then cutting the extended filling 70 threads close to the end of the cloth package.

2. The process or method of finishing a cloth selvage which consists in subjecting the end of a cloth package to the action of air currents to distend unwoven portions of 75 thread from the cloth selvage, then parting the distended unwoven portions of threads close to the cloth selvage, and carrying the parted thread away from the cloth.

3. The process or method of finishing a 80 cloth selvage, which consists in forming the cloth into a package and moving the selvage end portion of the cloth package over induced air currents to extend unwoven portions of thread from the end of the package, 85 then separating the threads from the cloth selvage while extended therefrom.

4. The process or method of removing filling threads from a cloth selvage, which consists in subjecting the end of a roll of cloth 90 to the action of air currents to extend the filling threads, and then parting the extended filling threads, and removing them from the field of operation.

5. A machine for finishing a cloth selvage, comprising, in combination, a support 95 over which the selvage end of a cloth package may be moved, parting means acting in a plane non-coincident with the surface of said support for parting threads projecting 100 from the cloth selvage, and means for inducing air currents through said support to draw unwoven portions of threads from the cloth selvage into the field of operation of said parting means. 105

6. In a machine of the character described, the combination of a casing having a supporting surface over which the end of a bolt of cloth may be passed and provided with an opening, a cutting device in said 110 opening below the plane of the said supporting surface, and means for inducing air currents through said opening to draw unwoven portions of threads from the end of the bolt of cloth into the field of operation of the 115 cutting device.

7. In a machine of the character described, the combination of a supporting surface having an opening over which the end 120 of a roll of cloth may be moved while sustained upon said surface, a thread parter mounted to act upon threads extending into said opening from the end of the cloth roll, and means for inducing air currents into said opening to distend unwoven threads 125 from the cloth roll passed over said opening and place them in the field of operation of the thread parter.

8. A machine of the character described, comprising, in combination, a support hav- 130

- ing an opening over which the selvage edge of a cloth package may be passed, a cutting device mounted to act upon threads extended from the cloth selvage, and means for inducing air currents through said opening to cause unwoven portions of threads along the cloth selvage to be extended into the field of operation of the cutting device.
9. In a machine for finishing cloth sel-
10 vages by cutting therefrom unwoven portions of filling threads, the combination of a sup-
port having a guiding surface and an opening over which the selvage end of a cloth package may be passed, means for inducing
15 air currents into said opening to extend unwoven portions of filling threads from the cloth selvage, and a thread cutter mounted to cut threads extended into said opening as the cloth package is moved over the opening.
- 20 10. In a machine for finishing cloth sel-
vages by cutting therefrom unwoven portions of filling threads, the combination of a support having a guiding surface and an opening over which the selvage end of a
25 cloth package may be passed, means for inducing air currents into said opening to ex-
tend unwoven portions of filling threads from the cloth selvage, a thread cutter mounted to cut threads extended into said
30 opening as the cloth package is moved over the opening, and means to protect the sel-
vage of the cloth from the action of the cutter.
11. In a machine of the character de-
35 scribed, the combination of a casing having a supporting surface provided with an opening over which the selvage end of a cloth package may be passed as it is moved along said supporting surface, pneumatic means
40 for causing unwoven portions of threads to be extended from the cloth selvage into said opening, and means for cutting the threads extended into said opening from the cloth selvage.
- 45 12. In a machine of the character de-
scribed, the combination of a work support-
ing surface having an opening over which the edge of a cloth package may be passed, thread cutting means acting in a plane below the
50 plane of the supporting surface, and means for inducing air currents into said opening to extend unwoven portions of thread along the cloth edge into the plane of the thread cutting means.
- 55 13. In a machine of the character de-
scribed, the combination of a work support-
ing surface having an opening over which the edge of a cloth package may be passed, thread cutting means acting in a plane below
60 the plane of the supporting surface, means for inducing air currents to said opening to extend unwoven portions of thread along the cloth edge into the plane of the thread cutting means, and means for adjusting the
plane of action of the thread cutting means 65 toward and from the supporting surface to vary the distance the threads shall be cut from the cloth edge.
14. In a machine for cutting unwoven portions of threads from the edge of a woven cloth after it has been formed into a roll or package, the combination of a work sup-
porting surface having an opening over which the end of a roll of cloth may be moved while the roll is sustained endwise 70 relative to the supporting surface, thread cutting means for severing threads project-
ing from the edge of the roll of cloth as the latter is moved over said opening, an air conduit having an inlet below the plane of 75 the supporting surface, and means for in-
ducing air currents through said opening into said conduit to extend unwoven portions of threads from the edge of the roll of cloth into position to be cut and then carry 80 away the severed portions of thread.
15. In a machine of the character de-
scribed, the combination of a frame or cas-
ing having a work supporting surface on
which the end of a roll of cloth may rest, 85 a block mounted on said frame or casing, a thread cutter mounted in said block below the work supporting surface, and an air con-
duit in communication with said block, and
means for inducing air currents in said con-
duit to position unwoven portions of threads along the end of a cloth package for the 90 action of the thread cutter.
16. In a machine of the character de-
scribed, the combination of a frame or cas-
ing having a work supporting surface adapted to sustain a roll of cloth endwise with the end of the roll of cloth on said 95 surface, a block mounted on said frame or casing, a thread cutter mounted in said block 100 below the work supporting surface, and an air conduit in communication with said block, means for inducing air currents in said conduit to position unwoven portions of threads along the end of a cloth package for 105 the action of the thread cutter, and means for adjusting the thread cutter toward and from the work supporting surface.
17. In a machine of the character de-
scribed, the combination of a thread parter, 110 means for directing the selvage end of a roll of cloth in a path of movement adjacent to said thread parter, means for extend-
ing unwoven portions of thread from the selvage of the roll of cloth into the field of action of the thread parter as the end of the roll of cloth is moved along the direct-
ing means, and means for actuating the 115 parter to part the extended threads adjacent to the cloth selvage.
18. In a machine for finishing the selvage edge of a piece of woven cloth, the combina-
tion of a thread parter, means for guiding
120
125

the selvage edge of a roll of cloth close to the thread parter as the roll of cloth is moved relatively thereto with the end of the roll of cloth opposite the parter, means 5 for causing any unwoven ends of weft or filling threads along the edge of the roll of cloth to be extended from the cloth selvage into the field of action of the thread parter

as the selvage edge is moved relatively thereto, and means for actuating the parter to 10 part the weft or filling ends close to the cloth selvage at the end of the cloth roll.

In testimony whereof I have signed my name to this specification.

HERBERT W. OWEN.
